UNITED STATES PATENT OFFICE.

TIMOTHY O'SHEA, OF CHICAGO, ILLINOIS.

WINDOW-BEAD FASTENER.

SPECIFICATION forming part of Letters Patent No. 670,595, dated March 26, 1901.

Application filed March 2, 1899. Serial No. 707,468. (No model.)

To all whom it may concern:

Be it known that I, TIMOTHY O'SHEA, a citizen of the United States of America, residing at Chicago, in the county of Cook and State 5 of Illinois, have invented certain new and useful Improvements in Window-Frames, of which the following is a specification.

My invention relates to certain improvements in window-bead fasteners, the purpose 10 being to provide for the convenient removal of securely-held front or rear sash.

The invention is illustrated in the drawings by means of six figures, of which—

Figure 1 is a perspective of the left-hand 15 portion of the window frame and sash. Fig. 2 is a vertical section in line 2 2 of Fig. 4. Fig. 3 is a similar section in line 3 3 of the same figure. Fig. 4 is a horizontal section in the crooked line 4 4 of Fig. 1. Fig. 5 is a 20 perspective of a spring-clip, and Fig. 6 is a perspective of a device for engaging said spring-clip adapted for attachment to the window-stop.

Referring to the drawings, and especially 25 to Fig. 4, A is the ordinary jamb, and B the blind-stop. The jamb is vertically grooved at a, as is customary, and the parting-strip C is held in said groove. Said parting-strip is, however, composed of an upper stationary 30 portion c, a lower stationary portion c', and an intermediate removable portion c². The lower end of the upper stationary portion of the parting-strip is beveled, and the upper end of the lower stationary portion is under- 35 cut. The adjacent ends of the removable portion are correspondingly shaped, so that its lower end may be thrust behind the portion c' and crowded into place. The removable portion of the parting-strip is held in 40 place by a spring-clip H, preferably formed, as here shown, with a flat bottom h and inwardly-curved sides h' h². The flat bottom is perforated, and a perforated plate or rectangular washer I is placed against said bottom, a screw J being passed through both and 45 driven into the jamb to secure the spring-clip in place. When the removable piece of the parting-strip is forced into this clip, it is held there by the pressure of the inwardly-curved 50 sides, and to afford a better grip upon the latter I prefer to form the strip as shown in Fig. 4, in which that portion of the strip which

lies within the groove has inwardly-concaved sides g⁴ g⁵.

This device or substantially the same may 55 be employed to secure the window-stop D in place, so as to be easily removed and replaced. For this purpose the jamb may be provided with a groove beneath the window-stop like the groove in which the parting-strip rests, or 60 small portions of said groove, as seen at a', may be provided to receive spring-clips H', like the clips H, and the window-stop may be provided with short blocks d, fastened to it by any suitable means, as by means of screws 65 passing through holes d'; these blocks corresponding to short portions of the parting-strip within the groove. In the case of the window-stop, however, I prefer to provide a removable portion D', having a pointed upper 70 end d², beveled to pass beneath the lower undercut end of the upper stationary part D² of the stop which is fitted thereto.

It is of course obvious that the removable 75 portions of the stops or parting-strips referred to in this specification may consist of the entire stop or strip, the only advantage in having a part of the strip stationary in certain cases being that it is easier to handle in taking it out and replacing it than the entire 80 strip would be.

I claim as new and desire to secure by Letters Patent—

1. In a window-frame, the combination with 85 jamb and strip members one of which is provided with a longitudinal groove and the other with a laterally-recessed longitudinal rib adapted to extend nearly to the bottom of said groove, of a U-shaped spring-clip fixed to the bottom of the groove and adapted to 90 engage the recessed rib at any point of the length of the latter; whereby the rib is rigidly held against lateral displacement in the plane of the grooved member and yieldingly held against withdrawal from the groove, 95 both by a clip which need not be accurately located along the groove.

2. The combination with a jamb provided 100 with a groove parallel to the sash, of the clip having its base fixed to the bottom of the groove, and its resilient end portions bent at right angles to said base and centrally curved inward, and a stop covering the groove and provided with a rigid longitudinal rib of uni-

form cross-section substantially fitting and filling the space within said clip; whereby the necessity for accurate location of the clip is avoided and the clip yieldingly resists withdrawal of the rib and rigidly resists its movement from the sash.

5 In witness whereof I have hereunto set my

hand, at Chicago, in the county of Cook and State of Illinois, this 25th day of February, A. D. 1899.

TIMOTHY O'SHEA.
